United States Patent Office.

JOHN HARWOOD, OF ALBANY, NEW YORK.

Letters Patent No. 99,084, dated January 25, 1870.

IMPROVED BOOT-STRETCHER.

The Schedule referred to in these Letters Patent and making part of the same.

To all whom it may concern:

Be it known that I, JOHN HARWOOD, of Albany, in the county of Albany, and State of New York, have invented certain new and useful Improvements in Boot and Shoe-Stretchers; and I do hereby declare that the following is a full, clear, and exact description thereof, reference being had to the accompanying drawings, forming a part of this specification, and to the letters of reference marked thereon, in which—

Figure 1 is a vertical central section of my invention.

Figure 2 is a horizontal section, taken on the plane of line $x x$ in fig. 1.

Figure 3 is a view of front portion of fig. 2, having levers $Z Z$, in place of wedge L .

Similar letters of reference indicate like parts in all the figures.

The principal object of my invention is so to construct a boot and shoe-stretcher, that either the toe or the instep, or both, of a shoe or boot may be stretched, as desired; and this is to be effected by using one stretcher, instead of two separate ones, as the common practice now is. This object I accomplish by constructing my improved stretcher as follows:

The last or stretcher is made in three parts, designated by letters $A A$ and B . The upper part B is divided from the two lower parts $A A$, on the plane of the line $a a a a$, as shown in fig. 1.

To keep the upper part B of the stretcher in its place, I screw, or otherwise fasten into its front end, a wire, N , bent at right angles, the bent end of which moves in a hole made in one of the two lower parts $A A$ of the stretcher.

The two lower portions $A A$ of the last or stretcher consists of two equal parts, divided by a central vertical plane, as shown in fig. 2, and connected together at the heel by a suitable hinge, R .

The mechanism by which I operate my improved stretcher is clearly shown in figs. 1, 2, and 3, and consists of a horizontal rod or shaft, C , having a wedge-shaped head, I , as shown in fig. 2, or connected to two links, $Z Z$, forming a toggle-joint, as shown in fig. 3, which latter mode is, perhaps, preferable.

The wedge L , or levers $Z Z$, are connected by a long nut, Y , to the front end of rod or shaft C .

Shaft C is supported, at its back end, by a suitable bearing, O , as shown in fig. 1.

Near the back end of shaft C , I construct the upper shaft D and its attachments, as follows:

Shaft D runs through the top of the stretcher B , through a suitable oblong aperture.

At the bottom of shaft D I secure a bevel-wheel, K , which engages with a similar wheel fastened upon shaft C , as seen in figs. 1 and 2.

On the upper end of shaft D , I attach a cross-handle, or a wheel, H , as seen in fig. 1.

Between the wheel H and the top of the instep-stretcher B , I employ a hollow rod or sleeve, J , which slides easily upon shaft D .

The upper end of sleeve J is enlarged, and has a screw-thread cut in it, as shown at E , in fig. 1, for the reception of screw F , as shown in the same figure.

The lower end of sleeve J is connected, by links M , to the back part of instep-stretcher B , as shown in fig. 1.

Wedge L slides in a horizontal slot, T , in each half of the toe-stretcher $A A$, as shown in fig. 2.

The three parts, $A A$, and B , of the stretcher, may be made of solid wood, similar to a shoemaker's last; or they may be made hollow, and of cast-iron, or other suitable metal.

At any convenient point on the shaft D , I secure a collar, W , which serves as a bearing to support screw F , to prevent it from sliding down the shaft D .

Screw F is centrally perforated, with an aperture a little larger in diameter than shaft D .

It will be seen from the above, that when the handle or wheel H is turned, the wedge L will be propelled forward or backward by the nut Y , and the toes of the stretcher will be separated, or permitted to close together, as may be required.

It may also be seen that a great advantage will be gained by the use of my improved stretcher, inasmuch as a boot may be stretched across the toes or in the instep, and then, without losing the stretch so obtained, the handle or wheel G or H , as the case may require, can be operated to stretch its corresponding connected parts, that is, either the toe or the instep.

What I claim as new, and desire to secure by Letters Patent, is—

The shaft D , bevel-wheels K and I , shaft C and wedge L , or links $Z Z$, and lower sections $A A$, in combination with sleeve J , screw F , links M , and upper section B , of a boot and shoe-stretcher, constructed and operating substantially as and for the purpose herein shown.

JOHN HARWOOD.
